(57) **CLAIM**

The ornamental design for a mouthpiece for instrument with aligned ligature holes, as shown and described.

DESCRIPTION

FIG. 1 is a first isometric view of the mouthpiece for instrument with aligned ligature holes;

FIG. 2 is a second isometric view of the mouthpiece for instrument with aligned ligature holes;

FIG. 3 is a right-side view of the mouthpiece for instrument with aligned ligature holes;

FIG. 4 is a left-side view of the mouthpiece for instrument with aligned ligature holes;

FIG. 5 is a top view of the mouthpiece for instrument with aligned ligature holes;

FIG. 6 is a bottom view of the mouthpiece for instrument with aligned ligature holes;

FIG. 7 is a front view of the mouthpiece for instrument with aligned ligature holes; and,

FIG. 8 is a back view of the mouthpiece for instrument with aligned ligature holes.

The broken lines represent the portions of the design that form no part of the claim.

1 Claim, 8 Drawing Sheets
